Sneer & Marx,

Piano Sounding Board,

No 9,287.

Patented Sept. 28, 1852.

UNITED STATES PATENT OFFICE.

A. SPEER AND E. MARX, OF AQUACHANOCK, NEW JERSEY.

SOUNDING-BOARD OF PIANOFORTES, &c.

Specification of Letters Patent No. 9,287, dated September 28, 1852.

To all whom it may concern:

Be it known that we, ALFRED SPEER and ERNEST MARX, of Aquachanock, in the county of Passaic and State of New Jersey, have 5 invented a new and useful Improvement in Sounding-Boards and Their Appendages of Pianofortes and other Stringed Musical Instruments; and we do hereby declare that the following is a full, clear, and exact description of the same, reference being had to the accompanying drawings, forming part 10 of this specification, in which—

Figure 1, is a perspective view showing the sounding board of a piano forte with all 15 the parts to which the strings are connected, the same being constructed according to our improvements. Fig. 2, is a longitudinal section of the same. Fig. 3, is an end view, and Fig. 4, a transverse section.

20 Similar letters of reference indicate corresponding parts in each of the several figures.

The nature of this invention consists in making the sounding board in the form of 25 a hollow cylinder, cylindroid, cone, or prism, or part of either of such figures, the said board having its ends secured between two disks or heads. The strings, cap, tuning block, and all parts of the instrument are 30 suitably arranged around it to produce the sound. The principal object of making the board of this form is to improve the sound, but we believe there are also other advantages, of which one we will mention is that 35 it will afford facility for making a double instrument, or an instrument with two sets of strings in one case.

To enable those skilled in the art to make 40 and use our invention we will proceed to describe its construction and operation.

A, is the sounding board which is represented to be in the form of a hollow cylinder; it is secured between two very strong wooden disks or heads B, and C, which are 45 braced together by braces D, D, and may be further strengthened by tension rods as shown at a. The disk C, serves as the tuning block, the tuning pins b, b, being screwed into its periphery.

50 E, is the cap which may be made of cast iron as in the instruments in use; it is in the form of part of a cylinder so that all parts of its face may be at equal distances from the sounding board; it rests upon and

is firmly secured to the disk B, having a 55 deep flange c, which extends over the outside or back of the disk, and being recessed all around at d, d, (see Figs. 1 and 2,) so as to fit over the periphery of the disk; the flange and recess are to insure firmness. 60

The strings e, e (only a few of which are shown) are secured by loops to the pins f, f, in the cap and pass through holes in the cap (as shown in Fig. 2), thence over the bridge g, h, to the tuning pins b, b. 65

The sounding board as we have shown it is a perfect unbroken cylinder, but it is quite possible that in some respects it might be better or at any rate as well with a part of the cylinder cut out or with a number of 70 slots cut longitudinally in it. Though we consider the circular or part circular the best form for the transverse section of the board, and have no intention to depart from that form; still we think that the same advantages may be obtained in almost an equal degree by making it elliptical, polygonal, or part polygonal, and for that reason we do not wish to confine ourselves closely to the circular or part circular form. 75

We consider all of the above-named forms to be equivalent to each other provided no support is given to the board except that afforded by the disks or heads B, and C. 80

It may be necessary to state that either 85 of the above forms or arrangements of the sounding board requires the cap, the tuning block, bridges, strings and all parts attached or connected thereto to be formed, or arranged in a similar manner.

What we claim as our invention, and desire to secure by Letters Patent, is—

Making the sounding board A, of a piano forte or other stringed musical instrument and arranging the strings and all appendages thereto, in the form of a cylinder or part of a cylinder or in any of the forms we have mentioned as considered to be equivalent, the said board having its ends secured between two disks or heads B, and 95 C, and having no other support except that derived from the said disks or heads. 100

ALFRED SPEER.
ERNEST MARX.
